(57) **CLAIM**

The ornamental design for a folding base, as shown and described.

DESCRIPTION

FIG. 1 is a perspective view of a folding base showing my new design in an open position;

FIG. 2 is a front view thereof, with the rear, left side, and right side views being identical;

FIG. 3 is a front, left side view thereof;

FIG. 4 is a top view thereof;

FIG. 5 is a bottom view thereof;

FIG. 6 is an exploded perspective view thereof;

FIG. 7 is a front view showing the lower portion of folding base of FIG. 1 separately in a folded position; and,

FIG. 8 is a front, left side view thereof.

1 Claim, 8 Drawing Sheets
